UNITED STATES PATENT OFFICE.

HEINRICH FRIEDRICH HAMBRUCH, OF HAMBURG, GERMANY, ASSIGNOR TO
AUG. F. RICHTER, OF SAME PLACE.

BUTTON OR STUD.

SPECIFICATION forming part of Letters Patent No. 395,973, dated January 8, 1889.

Application filed October 3, 1888. Serial No. 287,071. (No model.)

To all whom it may concern:

Be it known that I, HEINRICH FRIEDRICH HAMBRUCH, a subject of the German Emperor, and a resident of Hamburg, in the German Empire, have invented certain new and useful Improvements in Detachable Buttons or Studs, of which the following is a specification.

My invention relates to that class of detachable buttons or studs in which the fastening is effected by means of folding wings or flaps; and the object of my improvement is to afford means for automatically operating the folding wings after having passed the button-hole. I attain this object by the mechanism illustrated in the accompanying drawings, in which—

Figures 1 and 2 represent the button with the folding wings in the position when entering the button-hole. Fig. 3 is a side view, with unfolded wings. Fig. 4 is a view of Fig. 2 from below. Fig. 5 shows a vertical section of my improved fastening device in enlarged scale; and Fig. 6, a vertical section of a button provided with a fastening device of a somewhat modified construction, also in enlarged scale.

Similar letters refer to similar parts throughout the several views.

The button *a* is connected to a plate, *g*, which is provided with the arms *e e*, serving to arrest the folding wings *f f*, pivoted at *n n* to the shank *c* in both their extreme positions. The shank *c* is movable between and in the direction of said arms *e e*, the ends of which bear through suitable holes, *i i*, of the wings *f f* against the heads *m* of the latter, which are formed on this side eccentrically to the pivots *n n*, so that the arms, which have the tendency of a spring under certain conditions, are actuating the wings *f f*. The latter are arrested in their extreme positions under the action of the elastic arms *e e* as soon as the square parts of the heads of the wings meet with their faces, Figs. 1 and 2. For this reason the holes of the shank *c*, in which the wings rest, are slightly elongated in order to allow a certain play to the pivots *n* of the wings. It will therefore be understood from the drawings that by causing the shank *c* to

depart from the button-plate *g* when the wings are in the position Figs. 1, 2, and 5 the wings must unfold automatically. To effect this, either a pair of crank-levers, *h h*, bearing against the button-plate *g* and the blunt end of the shank *c*, or a rod, *k*, Fig. 6, passing through the plate *g* and the button, is employed.

The operation of this locking device will be as follows: In the position shown in Figs. 1, 2, 4, and 5 the button is to be introduced into the button-holes until the ends of the levers *h h* touch the adjacent solid material of the objects to be joined together by the button, when the levers *h h* will rock on the plate *g*, whereby the wings *f* are forced into the position shown in Fig. 3, in which the device is locked, and the long arm of the levers touches the button-plate *g*. When detaching the button from the objects held together as described, only one of the wings *f* needs to be turned in line with the shank *c*, whereupon the other wing will follow correspondingly, thereby the shank *c* being pushed toward the button-plate *g* and the levers *h h* caused to occupy their original position, Figs. 1 and 5. When employing the rod *k*, Fig. 6, to act upon the shank *c*, a slight pressure on the knob *k'* is required to lock the fastening device automatically.

I am aware that prior to my invention detachable buttons and studs have been made with vibrating wings pivoted to the shank of a button. I therefore do not claim such combination, broadly; but

What I do claim as my invention, and desire to secure by Letters Patent, is—

1. As an improvement in detachable buttons or studs, the button herein described having the spring-arms *e e* secured thereto, the movable shank disposed between said spring-arms, and the wings *f f*, pivoted to said shank and acted upon by said spring-arms, substantially as set forth.

2. As an improvement in detachable buttons or studs, the button herein described having the plate *g*, the spring-arms secured thereto at their upper ends, movable shank disposed between said spring-arms, the wings *f f*, pivoted at their inner ends to said shank

and having holes or openings through which the lower ends of said spring-arms project, and the levers *h h*, secured to said plate *g*, bearing at their inner ends upon said shank, 5 substantially as set forth.

In testimony that I claim the foregoing as my invention I have signed my name, in pres-

ence of two witnesses, this 11th day of August, 1888.

HEINRICH FRIEDRICH HAMBRUCH.
